UNITED STATES PATENT OFFICE.

EMIL KRALL, OF TOLEDO, OHIO, ASSIGNOR TO THE CORONA CUT GLASS COMPANY, OF TOLEDO, OHIO, A CORPORATION.

DESIGN FOR A DRINKING-GLASS OR TUMBLER.

46,806.

Specification for Design.

Patented Dec. 29, 1914.

Application filed April 13, 1914. Serial No. 831,644. Term of patent 3½ years.

To all whom it may concern:

Be it known that I, EMIL KRALL, a subject of the Emperor of Austria-Hungary, residing at Toledo, in the county of Lucas, State of Ohio, have invented a new, original, and ornamental Design for a Drinking-Glass or Tumbler, of which the following is a specification, reference being had to the accompanying drawing, forming part hereof.

The figure is a perspective view of a tumbler showing my new design.

I claim:

The ornamental design for drinking glass or tumbler as shown.

EMIL KRALL.

Witnesses:

GEO. H. BECKWITH,
GERTRUDE BRACKER.
